Primary Examiner—Janice E. Seeger*Attorney, Agent, or Firm*—George F. Bethel; Patience K. Bethel[57] CLAIM

The ornamental design for a food service cover and support, as shown and described.

DESCRIPTION

FIG. 1 is a perspective view of the food service cover and support with a broken line showing of a food service bar thereunder for illustrative purposes only and forms no part of the claimed design;

FIG. 2 is a top plan view;

FIG. 3 is an end view looking from either side of the food service cover and support;

FIG. 4 is a front elevation view; and,

FIG. 5 is a bottom plan view looking upwardly at the food service cover and support.
